[57] CLAIM

The ornamental design for a goblet, as shown and described.

DESCRIPTION

FIG. 1 is a front perspective view of a goblet showing my new design;

FIG. 2 is a left side elevational view thereof of FIG. 1,
the right side elevational view of FIG. 1 being a mirror
image thereof; and

FIG. 3 is a top plan view of the goblet showing my new
design.

FIG. 1

FIG. 2

FIG. 3
